UNITED STATES PATENT OFFICE.

CHARLES O. APPLEBY, OF NEW HAVEN, CONNECTICUT, ASSIGNOR OF ONE-HALF TO MILES J. HOTCHKISS, OF SAME PLACE.

POWDER-DIVIDER.

SPECIFICATION forming part of Letters Patent No. 598,970, dated February 15, 1898.

Application filed June 3, 1897. Serial No. 639,232. (No model.)

To all whom it may concern:

Be it known that I, CHARLES O. APPLEBY, of the city and county of New Haven, in the State of Connecticut, have invented a new and useful Improvement in Powder-Dividers, fully set forth and described in the following specification, taken in connection with the drawings, which form a part thereof, and in which—

10 Figure 1 is a perspective view of the lever; Fig. 2, a vertical section on lines 2 2 of Fig. 1; Figs. 3 and 4, side elevations of the divider, a portion of the casing being removed; Fig. 5, a bottom view of the same; Fig. 6, an elevation on the opposite sides from Figs. 3 and 4; Fig. 7, a detail view of one of the dividers.

In all figures similar letters of reference represent like parts.

20 This invention relates to powder-dividers, and has for its object the construction of a device for accurately dividing medicinal powders and like substances into equal portions, so that each portion shall contain a similar 25 quantity of powder—a most important element in the putting up of medicines.

In the drawings, A represents a substantially rectangular frame, of steel or other suitable material, for receiving the powder, having an extension a', on which are mounted vertical rods a², of similar material. A number of blocks B, of steel or other suitable material, are adapted to fit within the frame A and when all are assembled therein to completely fill the interior space thereof, the various blocks being of unequal width, as shown in Fig. 1, so that by the arrangement of one, two, or three of these blocks the interior space of the frame may be divided into various proportions, as may be desired by the operator.

30 L-shaped arms b, having vertical portions b', are rigidly secured to the blocks B and have longitudinal perforations in their vertical portions, so that they may fit over the rods a² and be raised and lowered thereon by means of lugs b² on said arms b, as shown in Fig. 1. Clamps b⁴ are also attached by set-screws b⁶ or other means to the blocks B, so that two or more of said blocks may be fastened together, so as to provide any desired arrange-

ment of the blocks to divide the space in the frame.

C represents a hollow casing consisting of the sides c and c' and top c², the side c' being removed in Figs. 3 and 4. At one end of the 55 casing is secured a handle c⁵.

Within the casing C is secured the dividing mechanism, consisting of the plates d and d', affixed to the ends of said casing, secured to which plates are a series of horizontal rods 60 E, arranged one above the other, and on which are adapted to slide tubes E'. A horizontal guide-rod F is secured at its ends to the lower edge of said casing. Integral with or rigidly secured to the forward ends of the tubes E' 65 are depending vertical carriers G, of different lengths, so that their lower ends terminate in the same horizontal plane. These lower ends are looped or perforated to surround the guide-rod F and are adapted to carry parallel blades 70 O, extending transversely to the guide-rod. A blade N is rigidly secured to the guide-rod F to be in the rear of and parallel to the movable blades O and project downward slightly farther than the blades O. 75

An operating-lever L is pivoted at l on the exterior face of the side c of the casing (see Fig. 6) and carries at its lower end a gear l', which is adapted to mesh with a pinion K on the arbor k, which extends through the side 80 c of the casing and is journaled in a bearing H, connected to the inner side of the casing above the stationary blade N. A thumb-plate l² is provided at the upper end of the operating-lever L, so that the operator by 85 pressing the operating-lever in one direction or another turns the pinion K and arbor k in a reverse direction.

Within the casing and rigidly mounted on the arbor k to rotate therewith is a vertical 90 lever I, having a series of rods i pivoted thereto, one above the other, and the other ends of which are severally pivotally secured to the upper ends of the depending carriers G. These rods i are of such varied lengths 95 that when the lever I is in its rearward position, Fig. 4, the carriers will be drawn into juxtaposition with each other and when the lever is swung rearward the carriers will each be forced proportionately forward, so that the 100

relative distance between them will be increased, while each will remain equidistant from the others.

A frame M, of wire or other suitable material, is secured at its ends to the bottom edge of the side c of the casing in well-known manner, and has at its outer end a vertical extension m, adapted to form, with the stationary blade N, a support when said device is in use.

10 In operation the powder to be divided is put into the frame A or so much of the frame as is desired to be used, the remainder being occupied by a block or blocks. The powder is then leveled by the successive raising and lowering of the rest of the blocks, which are fastened together, as pointed out above. The frame A is then raised from the pill tile or table on which it may rest and the powder is forced out of the frame by the block or blocks.

15 B. The powder is then left on the pill-tile in rectangular form, the depth through being equal. The blades of the divider or cutting device are then set with the desired space between them for cutting the powder into the requisite number of units. As the operating-lever L is forced rearward by the thumb of the operator on the thumb-plate it causes the gear l' to revolve the pinion K and thus rotate the lever I in the opposite direction,

20 which, by means of the rods i, secured to the carriers G, forces the carriers and blades secured thereto apart to separate the different layers or units of powder. The divider is then raised from the powder, the blades drawn back to their original positions by the reverse movement of the operating-lever, and are then placed on the powder in a direction at right angles to their former position and the operation repeated to divide the powder

25 into squares. It will thus be seen that the cake of powder may be divided into the desired number of units by the cross-cutting of the cake, and at the same time each unit will be of exactly the same proportion in all directions.

45 Having now described my invention, what I claim, and desire to secure by Letters Patent, is—

1. In a powder-molding device, the combination with a substantially rectangular frame; a number of removable blocks of various widths adapted to together fill the interior space of said frame; and means for raising and lowering each block separately to level the substance within the frame, substantially as described.

2. In a powder-molding device, the combination with a substantially rectangular frame; of a number of removable blocks of various widths adapted to together fill the interior space of said frame; and means for raising and lowering said blocks separately or collectively to level the substance within the frame, substantially as described.

65 3. In a powder-molding device, the combination with a substantially rectangular frame;

of a number of removable blocks of various widths adapted to together fill the interior space of said frame; vertical rods on which said blocks are adapted to slide; clamps for fastening the various blocks together; and means for raising and lowering said blocks to level the substance within the frame, substantially as described.

4. In a powder-divider, the combination with a frame; of carriers adapted to slide longitudinally on said frame, carrying depending blades extending at right angles to the direction of movement of the carriers; and mechanism for simultaneously varying the distance between said carriers while maintaining an equal distance between the several carriers and depending blades, substantially as described.

5. In a powder-divider, the combination with a horizontal rod or rods; of carriers adapted to slide on said rod or rods, carrying depending blades extending at right angles to said rod or rods; and a lever connected to said carriers to vary the distance between them while maintaining an equal distance between the several carriers and depending blades, as said lever is swung on its pivot, substantially as described.

6. In a powder-divider, the combination with a series of parallel horizontal rods; of tubes adapted to slide on said rods, having depending carriers with blades extending at right angles to said rods; and a lever connected to said carriers to vary the distance between them, while maintaining an equal distance between the several carriers and depending blades, as said lever is swung on its pivot, substantially as described.

7. In a powder-divider, the combination with a series of parallel horizontal rods; of tubes adapted to slide on said rods having depending carriers with blades extending at right angles to said rods; a stationary blade parallel to the other blades; and a lever connected to said carriers to vary the distance between them, while maintaining an equal distance between the several carriers and blades, as said lever is swung on its pivot, substantially as described.

8. In a powder-divider, the combination with a horizontal rod; of a tube adapted to slide thereon having a depending carrier carrying a blade; a stationary blade parallel to said blade mounted on said carrier; and a lever connected by a rod to said carrier to slide the tube on said rod, to vary the distance between said blades, as said lever is swung on its pivot, substantially as described.

9. In a powder-divider, the combination with a series of parallel horizontal rods; of tubes adapted to slide on said rods having depending carriers carrying blades extending at right angles to said rods; a pinion rigidly mounted on a rotary arbor; a vertical lever mounted on said arbor to rotate therewith, connected to said carriers to vary the distance

between them, while maintaining an equal distance between the several carriers and depending blades as said lever is swung on its pivot; and an operating-lever adapted to rotate said pinion as it is swung on its pivot, substantially as described.

5 In witness whereof I have hereunto set my

hand, at New Haven, in the county of New Haven, State of Connecticut, this 29th day of May, 1897.

CHARLES O. APPLEBY.
